CLAIM

The ornamental design for a doll, as shown and described.

DESCRIPTION

FIG. 1 is a front elevational view of a doll.

FIG. 2 is a rear elevational view thereof.

FIG. 3 is a left side elevational view thereof, the right side elevational view being a mirror image of the left side view.

FIG. 4 is a top plan view of the doll.

FIG. 5 is a bottom plan view thereof.

FIG. 6 is an alternate embodiment of the doll showing a front elevational view thereof.

FIG. 7 is a rear elevational view thereof.

FIG. 8 is a left side elevational view thereof.

FIG. 9 is a right side elevational view thereof.

FIG. 10 is a top plan view of the alternate embodiment of the doll; and,

FIG. 11 is a bottom plan view thereof.
